UNITED STATES PATENT OFFICE

123,600

DESIGN FOR A LOADING MACHINE

John Merck, Franklin, Pa., assignor to Joy Manufacturing Company, Franklin, Pa., a corporation of Pennsylvania

Application February 15, 1940, Serial No. 90,279

Term of patent 14 years

To all whom it may concern:

Be it known that I, John Merck, a citizen of the United States and residing at Franklin, in the county of Venango and State of Pennsylvania, have invented a new, original, and ornamental Design for a Loading Machine, of which the following is a specification, reference being had to the accompanying drawings, forming a part thereof, wherein:

Fig. 1 is a perspective view of the front and one side of a loading machine showing my new design;

Fig. 2 is a perspective view showing the rear and opposite side of the loading machine illustrated in Fig. 1.

I claim:

The ornamental design for a loading machine, as shown.

JOHN MERCK.
